AQUARIUM FILTER

Abby Halpert, Brooklyn, N.Y., assignor to Halvin Products Co., Inc., Brooklyn, N.Y., a corporation of New York

Filed July 6, 1965, Ser. No. 86,047

Term of patent 14 years

(Cl. D91—1)

FIG.1

FIG.5

The holes on the slightly elevated bottom surface continue throughout the surface as indicated by FIGURES 3 and 6.

I claim:

The ornamental design for an aquarium filter, substantially as shown and described.
